C. P. Goepel
ATTORNEY

UNITED STATES PATENT OFFICE.

EMIL BOMMER, OF BROOKLYN, NEW YORK.

HINGE.

Application filed December 23, 1921. Serial No. 524,372.

To all whom it may concern:

Be it known that I, EMIL BOMMER, a citizen of the United States, and a resident of Brooklyn, in the county of Kings and State 5 of New York, have invented certain new and useful Improvements in Hinges, of which the following is a specification.

The present invention relates to improvements in hinges and more particularly to a 10 pintle and its associated parts in which the pintle, which extends through the hinge barrel and forms the pivot point about which the hinge leaf swings, will be so interlocked with the leaf ear that extends over the end 15 of the barrel that there will be little likelihood of the occurrence of that relative rotation between pintle and its cap nut which would result in the separation of these parts and the consequent disassembly of the hinge 20 structure.

It is eminently to be desired that the 25 pintle, leaf and its ear and the cap nut be all made to rotate together during the operation of the hinge to avoid the tendency 30 of the cap nut to become loosened. The cap nut as is well known, is employed to bind the hinge parts together, and particularly to hold the leaf in proper relation to the barrel and to the pintle and for this reason 35 a continued tight engagement of the cap nut upon pintle is to be desired.

It is therefore an object of the invention 40 to secure this result without entailing any further considerable expense in the manufacture of the hinge and without sacrificing its strength or its ease of operation.

The invention also aims to effect a simplicity in the method of production of such 45 hinge parts and to secure simplicity in the hinge construction itself, and in general to arrive at the above desirable characteristics 50 in a hinge without adding to the parts thereof nor to the material and weight of the commercial product.

With the above and other objects in view, 55 the invention consists in the improved construction, combination, relative arrangement of the several parts and in the steps and processes of the method thereof as will 60 be hereinafter more fully described, illustrated in the accompanying drawing and subsequently incorporated in the subjoined claims.

In the drawing, wherein I have illustrated 65 one desirable and satisfactory embodiment

of the invention and in which similar reference characters designate corresponding parts throughout the several views—

Fig. 1 is a plan view of a double barrel hinge with one of the pintles and its cap 60 nut omitted;

Fig. 2 is a fragmentary elevation of a barrel with parts shown in section;

Fig. 3 is a cross section taken on the line 65 3—3 in Fig. 2;

Fig. 4 is a fragmentary side view of the pintle;

Fig. 5 is a section taken on the line 5—5 in Fig. 4; and

Figs. 6 and 7 are corresponding views of a 70 modified form, Fig. 6 being a side view of the pintle, and Fig. 7 a plan view of an ear provided with two flattened parts, the ear being for a single or double acting hinge.

Referring more particularly to the drawings, in Fig. 1 I have illustrated generally a construction of double barrel spring hinge in which 1 designates the central web connecting the two barrels, above which are placed the ears 2 and 3 of the leaves 4 and 5, the latter of which is provided with end flanges 6 which embrace the web 1 and the other leaf 4.

In accordance with the invention, the ear at one end of each leaf, such for instance as 85 shown in connection with the ear 3 in Fig. 1, is provided with a perforation 7 having a flat side 8 or other conformation to combine with a similar contour of the outer wall of the pintle 9 to secure an interlocking engagement or a non-rotatable connection between the pintle and the ear. In the construction as shown, the flat side wall 8 of the perforation extends within the circular 90 contour although it might be situated without the circle.

The pintle 9 as shown in Figs. 4 and 5 is operated upon to impart thereto a flat side face 10 extending for a suitable distance from each end thereof inwardly and merging at the inner end outwardly into the cylindrical outer surface of the pintle which results in the formation of a cam surface 11. This flattening of the pintle in the manner shown and described is preferably secured by swedging. The action of swedging produces sharp edges at the sides of the flattened surface, and these edges are rounded off by subsequently subjecting the pintle to the action of a die or other implement for 110

producing the screw threads 12 which are of a desirable pitch to take into the threaded socket of the cap nut 13. The cap nut is of any desired ornamental character and is 5 adapted to be screwed tightly against the outer face of the ear 3.

The ear 3 thus forms an abutment for the cap nut and by the turning of the nut, the pintle 9 is drawn through the barrel without, 10 however, permitting of its rotation because of the engagement of the flat side 10 with the flat wall 8 of the perforation 7. As the nut 13 is thus tightened, the cam surface 11 will gradually and by relatively 15 great pressure developed by the screw action be drawn up into the perforation 7 and into effectual binding engagement with the flat side wall 8 against which it frictionally binds.

20 The usual winding disk 14 is interposed between the end of the barrel, indicated at 15 in Fig. 2, and the ear 3, the pintle 9 passing axially through the barrel.

It will thus be appreciated that as the 25 hinge leaf 5 swings about the barrel, it will turn with it the ear 3, and because of the binding engagement just described, also the pintle 9 and its cap nut 13. The three parts thus rotating in unison will consequently not 30 induce any relative movement which might cause the backing of the nut 13 off the pintle threads 12.

A single act of swedging may suffice to produce the flat side face 10 on the pintle 35 and the sloping or curved surface 11, and the screw threading is preferably accomplished after the swedging action in order to compensate for any inequalities produced thereby and to smooth the sharp edges left 40 by the swedging. This swedging may be accomplished at a cost which is negligible and the resultant article is not weakened in any particular and forms a strong and binding engagement between the several parts.

45 Other means than swedging may be found advantageous. Also, instead of having the flattened side at only one point it may be on opposite points, as shown in Figures 6 and 7, which has an advantage in saving die 50 work and favors the screw threading dies when cutting the threads in giving a balanced cut. This flattening either at one or more sides may be provided at one end or both ends of the pintle.

55 I have herein disclosed an embodiment of the invention applied to a single barrel hinge which I have found to be very satisfactory and serviceable in use, and a method of producing hinge parts, but it will be 60 nevertheless understood that the invention is equally applicable for use in double barrel hinges, and the device is susceptible of many modifications in its structural form, such, for instance, as the use of a perforation and 65 pintle having more than one flat wall ar-

rangement of its several parts, and in the steps and processes of its manufacture, and I accordingly reserve the privilege of adopting all such legitimate changes as may be fairly embodied within the spirit and scope 70 of the invention as claimed.

What is claimed is:

1. The combination with a hinge barrel, 75 of a leaf having a laterally offset ear extending over the end of the barrel and provided with an irregular aperture, a pintle passing through said barrel and ear and provided with a threaded end extending beyond said ear and with a flattened shoulder adjacent said threaded end engaging a corresponding 80 wall of the aperture of said ear and a cap nut having a threaded engagement with the projecting end of said pintle and bearing at its inner end against said ear.

2. The combination with a hinge barrel, 85 of a leaf having a laterally offset ear extending over the end of the barrel and provided with an aperture having a flat wall, a pintle extending through said barrel and ear and provided with a mutilated threaded end, 90 adapted to pass through the aperture of said ear and with an inclined face bearing against the flat wall of said aperture and adapted to be jammed in said aperture, and a cap nut having a threaded engagement with the 95 end of said pintle and bearing at its inner end against said ear.

3. A hinge comprising a barrel, a leaf having an ear extending over one end of said barrel, said ear having a perforation with a 100 flat wall, a pintle extending through said barrel and the perforation of said ear and having a threaded end provided with a flat side terminating in a cam surface at the inner end of said flat side, and means 105 adapted to frictionally bind the pintle into locked contact against the wall of the ear perforation.

4. In a hinge having a barrel, a leaf having a laterally extending ear bearing upon the end of the barrel and provided with an irregular aperture, and a cap nut having a threaded recess, means for locking said leaf and cap nut together consisting of a pintle extending through said barrel and ear, 110 and provided with a threaded end, one side of said threaded end being mutilated to form a flat surface terminating in an inclined shoulder, the inclined shoulder engaging a straight edge of the aperture of said 115 ear, and the threaded end of said pintle engaging the threaded recess of said cap nut to firmly bind said ear and cap nut together.

5. The herein described method for forming 120 hinge parts which consists in initially swedging a hinge pintle, and subsequently screw threading the swedged portion of the pintle to round off the sharp edges caused by the swedging action. 125 130

6. The herein described method for forming hinge parts which consists in initially swedging a blank pintle at the ends thereof and in tapering off the inner edges of the 5 swedged portion into the cylindrical surface of the pintle, and subsequently screw threading the swedged portions to remove the

sharp edges resulting from the action of the swedge.

In testimony that I claim the foregoing 10 as my invention I have signed my name hereunder.

EMIL BOMMER.
